US00D705459S

(12) **United States Design Patent**
Decker

(10) **Patent No.:** **US D705,459 S**
(45) **Date of Patent:** **** May 20, 2014**

(54) **CANDLE OR OIL LAMP HAVING A PLANAR OR BENT PLANAR WICK**

(75) Inventor: **DayNa M. Decker**, Fountain Valley, CA (US)

(73) Assignee: **Lumetique, Inc.**, Fountain Valley, CA (US)

(**) Term: **14 Years**

(21) Appl. No.: **29/414,605**

(22) Filed: **Mar. 1, 2012**

Related U.S. Application Data

(63) Continuation-in-part of application No. 29/393,405, filed on Jun. 3, 2011, now Pat. No. Des. 678,558, which is a continuation of application No. 10/759,508, filed on Jan. 15, 2004, now Pat. No. 8,348,662, which is a continuation-in-part of application No. 10/300,695, filed on Nov. 19, 2002, now abandoned.
